UNITED STATES PATENT OFFICE

2,453,330

METHOD OF MAKING SPLIT PISTON RINGS

Lewis C. Marshall, East Walpole, Mass.

Application December 14, 1945, Serial No. 635,004

3 Claims. (Cl. 29—156.6)

1

The invention pertains to split piston rings, such as are used in the cylinders of internal combustion engines, for example, and more especially to a method of making such rings so that they will exert substantially uniform radial pressure upon the cylinder wall when in use, and to a novel ring resultant from the practice of such method. One of the principal difficulties encountered in the manufacture of split piston rings is that of so designing a split ring that when in use it will exert a uniform radial pressure against the cylinder wall. Rings of non-uniform radial section have been proposed as a means of overcoming this difficulty. It has also been proposed to employ an internal expander ring in association with the contact ring in order to supply the requisite expansive force and to secure uniform radial pressure. However, the manufacture of rings of non-uniform but accurate transverse section is difficult and expensive, while the employment of expander rings in association with contact rings involves difficulty in installation, in addition to the expense involved in making such composite rings.

In my prior Patent No. 1,783,047, dated November 25, 1930, I describe a method of making piston rings from steel wire by bending a length of wire or rod of uniform cross section and consisting of steel of from 0.5% to 0.8% carbon so as to form a single angular turn, severing said turn from the length of material to form an embryo ring having a gap at one point, and heating it sufficiently (while confining it both circumferentially and axially) to impart a permanent set, thereby to provide a ring of predetermined contour. The aforesaid patent suggests that by heating the ring while it is mounted upon and conformed to a mandrel of slightly elliptical transverse section, the finished ring, when placed in the cylinder, will exert approximately uniform radial pressure against the cylinder wall. While such a ring of approximately elliptical contour does exert a more uniform pressure against the cylinder wall than rings of true circular contour, an elliptical contour does not provide exact uniformity of radial pressure. I have now discovered a procedure whereby it is possible to impart to the uncompressed or open ring such a contour that when it is installed in a cylinder it actually exerts a uniform pressure against the cylinder wall throughout its entire periphery. The life of the ring and also that of the cylinder is thus prolonged; the passage of oil is reduced to a minimum; a better compression is attained, and it is unnecessary to resort to the use of

2

auxiliary expander rings or the like in order to secure the desired radial pressure. The best known mode of obtaining this result is hereinafter more fully described by reference to the accompanying drawings wherein

Fig. 1 is a diagrammatic plan view of a half ring showing the ring in its closed position in dotted lines and in its open or unstressed condition in full lines and indicating the deviation of a given point in the open ring from the corresponding position of said point in the closed or stressed ring;

Fig. 2 is a plan view, to smaller scale, of a split ring of the type to which the present invention relates, the ring being shown open or unstressed;

Fig. 3 is an edge view of the ring of Fig. 2;

Fig. 4 is another diagram showing a half ring in the closed or stressed condition and indicating the application of some of the mathematical terms employed in the discussion; and

Figs. 5 and 6 are tables of values representing the practical application of the present invention to the proper shaping of rings of specific dimensions.

When the terms "horizontal" and "vertical" are herein employed, they are used in a mathematical sense in defining the shape of the ring by reference to rectangular coordinates, with the axis of coordinates at the center of the ring and with the horizontal axis of coordinates bisecting the gap in the ring.

In accordance with the theory of elasticity, a beam of uniform transverse section fixed at one end and whose axis forms a circular arc, will deflect, when uniformly loaded with a radially acting load, according to the following Equations 1 and 2.

In these equations—

40 r_m =the mean radius of the beam.

r_a =the outside radius.

M =the moment of the load.

J =the moment of inertia of the ring section.

E =the modulus of elasticity of the ring material.

45 p =radial pressure per square inch acting on the mean radius of the closed ring, and $br_m d\varphi$ is the infinitesimal area at A corresponding to the infinitely small angle $d\varphi$.

Δx =the horizontal displacement from a true circle of any point P in the loaded beam at an angle φ_a from the fixed end, and Δy =the vertical displacement from a true circle of the same point in the loaded beam at an angle φ_a from the fixed end.

50 55 For a piston ring made from material, for in-

stance steel wire, of uniform rectangular transverse section, the moment of inertia is constant—

$$J = \frac{bh^3}{12}$$

where b =the axial thickness of the ring and h =the radial thickness of the ring.

With the above definitions of the terms employed, and referring to Figs. 1 and 4,

$$(1) \Delta x = \frac{r_m^2}{E} \left[- \int_0^{\psi_a} \frac{M}{J} \sin \phi d\phi + \sin \psi_a \int_0^{\psi_a} \frac{M}{J} d\phi \right]$$

$$(2) \Delta y = \frac{r_m^2}{E} \left[-(1 - \cos \psi_a) \int_0^{\psi_a} \frac{M}{J} d\phi + \int_0^{\psi_a} \frac{M}{J} (1 - \cos \phi) d\phi \right]$$

The differential moment at section B (Fig. 4) due to the force $pbrmd\phi$ acting on the differential area at A is expressed by the equation

$$(3) dM = pbr_m^2 \sin(\phi - \psi_a) d\phi$$

If the load is uniform along the mean circumference, there will be a positive moment at section B due to the load upon the arc BD as given by the equation

$$(4) M\psi_a = pbr_m^2 \int_{\psi_a}^{\pi} \sin(\phi - \psi_a) d\phi = pbr_m^2 (1 + \cos \psi_a)$$

This latter equation determines the moment at any section B (corresponding to the angle ψ_a) due to the uniform radial load acting on the mean circumference.

Substituting the value

$$\frac{bh^3}{12}$$

for the constant J , and substituting the value of $M\psi_a$ from Equation 4 in Equations 1 and 2—

$$(5) \Delta x = \frac{12pr_m^4}{Eh^3}$$

$$\left[\int_0^{\psi_a} (+\cos \phi) \sin \phi d\phi - \sin \psi_a \int_0^{\psi_a} (1 + \cos \phi) d\phi \right]$$

$$(6) \Delta y = \frac{12pr_m^4}{Eh^3} \left[(1 - \cos \psi_a) \int_0^{\psi_a} (1 + \cos \phi) d\phi - \int_0^{\psi_a} (1 - \cos \phi) (1 + \cos \phi) d\phi \right]$$

Integrating Equations 5 and 6, and substituting

$$Ax = 1 - \psi_a \sin \psi_a - \frac{\sin^2 \psi_a}{2} - \cos \psi_a$$

and

$$Ay = \frac{\psi_a}{2} + \sin \psi_a - \psi_a \cos \psi_a - \frac{\sin \psi_a \cos \psi_a}{2}$$

$$(7) \Delta x = \frac{12pr_m^4}{Eh^3} \cdot Ax$$

$$(8) \Delta y = \frac{12pr_m^4}{Eh^3} \cdot Ay$$

Substituting

$$\frac{pr_m}{r_a} = p_a$$

where p_a is the uniform radial pressure at the outer circumference (r_a being the outside radius)—

$$(9) \Delta x = \frac{12p_a r_a r_m^3}{Eh^3} \cdot Ax$$

$$(10) \Delta y = \frac{12p_a r_a r_m^3}{Eh^3} \cdot Ay$$

Equations 9 and 10 define the deviation from a true circular arc of any point P (Fig. 1) at an angle ψ_a measured from the fixed end of the beam and resultant from uniform loading.

Conversely, if a piston ring be so shaped, that when open or unstressed, every point in its circumference is displaced from a true circle so that the coordinates Δx and Δy of each such point are defined by Equations 9 and 10 it follows that when the ring is closed and confined within the cylinder, it will exert a uniform outward radial pressure p_a against the cylinder wall.

Thus, if the modulus of elasticity E of the material of the ring be known, and if the ring be of substantially uniform rectangular radial section, its open or unstressed shape may readily be determined by substituting the proper constants in Equations 9 and 10.

Specific examples of the shapes to be arrived at by the use of the above equations are shown in Figs. 5 and 6. Fig. 5, in tabular form, shows the departure from a true circular shape, of the unstressed or open ring, giving the radial distances measured outwardly from a true circle, for each degree measured from the mid-radius of the gap, the outside radius r_a of the closed ring being 1.8125 inches; h equaling 0.103 inch; b equaling 0.12375 inch; F equaling 9.75 lbs.; the

25 radial pressure p equaling 14.5 lbs. per square inch; E equaling 26,200,000; and the diameter of the base circle from which the radial distances are measured equaling 3.547 inches.

Fig. 6, likewise in tabular form, shows the departure from a true circular shape of the unstressed or open ring, giving the radial distances measured outwardly from a true or base circle for each degree measured from the mid-radius of the gap, the outside radius r_a of the closed ring being 35 1.656 inches; h equaling 0.109 inch; b equaling 0.1365 inch; F equaling 10 lbs.; the radial pressure p equaling 11 lbs. per square inch; E equaling 26,200,000; and the diameter of the base circle from which the radial distances are measured 40 equaling 3.150 inch.

The values in the above tables which fall within the width of the gap may be disregarded, but when preparing a heat treating mandrel for use in setting the ring to the required contour, it is desirable to shape the entire periphery of the mandrel in accordance with the tabulated dimensions.

Having thus accurately determined the proper contour of the unstressed or open ring, the contour may be imparted to the open ring in any usual or desired manner. For example, cast iron rings may be machined to this contour; steel rings may be formed as described for example in the patent to Marshall No. 1,783,047, and heat treated and set to shape, while open but confined about a non-circular mandrel contoured in accordance with Equations 9 and 10; or if the ring be moulded from plastic or other mouldable material, then the die or mould cavity may be contoured in accordance with Equations 9 or 10.

55 While it is not essential to the proper design of the ring as above described, it is of interest to note that a ring designed in accordance with Equations 9 and 10 may be closed by the application of a single force F applied at a point 90° from the gap where F equals $3br_m p_a$, this relation being deduced by a method of analysis generally similar to that employed in arriving at Equations 9 or 10.

I claim:

1. Method of making a split piston ring operative to exert substantially uniform radial pressure against the cylinder wall when installed in the cylinder and which, when so installed, has an outside radius r_a and a mean radius r_m , and wherein an embryo ring is first formed by bending a length 70 of steel wire to form an annular turn, cutting off

said turn from said length at such a point as to produce an approximately circular ring having a gap therein, placing the ring upon a mandrel and compressing and heat treating the ring to conform it to the mandrel, characterized in that the peripheral surface of the mandrel to which the ring is conformed differs from a true circle—the horizontal deviation Δx and the vertical deviation Δy from a true circle at any point at an angle $180^\circ - \psi a$ from the mid-radius of the location of the ring-gap on the mandrel being in accordance with the equations

$$\Delta x = \frac{12p_a r_a r_m^3}{Eh^3} \times A_x$$

and

$$\Delta y = \frac{12p_a r_a r_m^3}{Eh^3} \times A_y$$

where E is the modulus of elasticity of the ring material, h is the radial thickness of the ring, and where p_a is the desired uniform pressure in pounds per square inch at the outside circumference of the ring, and

$$A_x = 1 - \psi a \sin \psi a - \frac{\sin^2 \psi a}{2} - \cos \psi a$$

and

$$A_y = \frac{\psi a}{2} + \sin \psi a - \psi a \cos \psi a - \frac{\sin \psi a \cos \psi a}{2}$$

2. Method of making a split piston ring operative to exert substantial uniform radial pressure against the cylinder wall when installed therein and which will have an outside radius r_a and a mean radius r_m when installed in the cylinder, said method comprising as steps forming an embryo ring from material having a modulus of elasticity E and of uniform cross section, the radial thickness of the material of the ring being h , and permanently deforming the ring from a true circle to the extent that the horizontal and vertical deviations Δx and Δy , respectively, from a true circle, of any point in the uncompressed ring will be in accordance with the equations

$$\Delta x = \frac{12p_a r_a r_m^3}{Eh^3} \times A_x$$

and

$$\Delta y = \frac{12p_a r_a r_m^3}{Eh^3} \times A_y$$

where p_a is the desired uniform pressure in pounds

per square inch at the outside circumference of the ring, and

$$A_x = 1 - \psi a \sin \psi a - \frac{\sin^2 \psi a}{2} - \cos \psi a$$

and

$$A_y = \frac{\psi a}{2} + \sin \psi a - \psi a \cos \psi a - \frac{\sin \psi a \cos \psi a}{2}$$

3. Method of making a split piston ring operative to exert substantially uniform radial pressure against the cylinder wall when installed therein and which is of substantially uniform radial section and of a material having a modulus of elasticity E and an outside radius r_a and a mean radius r_m when installed in the cylinder, said method comprising as a step the formation of an open unstressed but elastic ring, of radial thickness h which deviates from a true circle, the horizontal and vertical deviations Δx and Δy , respectively, from a true circle, of any point in the unstressed open ring being in accordance with the equations

$$\Delta x = \frac{12p_a r_a r_m^3}{Eh^3} \times A_x$$

and

$$\Delta y = \frac{12p_a r_a r_m^3}{Eh^3} \times A_y$$

where p_a is the desired uniform pressure in pounds per square inch at the outside circumference of the ring, and

$$A_x = 1 - \psi a \sin \psi a - \frac{\sin^2 \psi a}{2} - \cos \psi a$$

and

$$A_y = \frac{\psi a}{2} + \sin \psi a - \psi a \cos \psi a - \frac{\sin \psi a \cos \psi a}{2}$$
